FIG-11.
FIG-12.

A cross-sectional view of a bearing assembly. It features a large outer ring with a textured outer edge. Inside the ring, there are two smaller rings: an inner ring and a middle ring. A horizontal cylindrical component, possibly a shaft or a pin, passes through the center of the rings. Several numbers are labeled around the assembly: '57' is at the top left, '151, 137' is on the inner ring, '170' is on the middle ring, '152' is on the left side of the inner ring, '141' is on the bottom left of the inner ring, '28' is on the right side of the outer ring, '46' is at the top right, and '45' is below it. There are also two small circular features, one at the bottom labeled '57' and another at the top left labeled '57'.

8 Claims. (Cl. 292—170)

1

This invention relates to a door lock or latch set construction wherein a spindle is moved slidably back and forth along its longitudinal axis to open and close a latch bolt. Locks or latch sets of this general character are known. The present invention provides a rugged lock construction which is relatively inexpensive to manufacture.

It is in general a broad object of the present invention to provide a novel and improved construction for a door lock or latch set of the character described.

A further object of the present invention is to provide a novel form of spindle construction for a door lock which is adapted to move a latch bolt upon longitudinal sliding movement of the spindle.

The invention includes other objects and features of advantage, some of which, together with the foregoing, will appear hereinafter wherein the present preferred forms of door lock are set forth.

In the drawings accompanying and forming a part hereof, Figure 1 is a transverse vertical section taken through a latch set embodying the invention, the view being taken more particularly along the line 1—1 in Figure 2.

Figure 2 is a section taken horizontally through a device embodying the present invention, the view being more particularly along the line 2—2 in Figure 1.

Figures 3 and 4 are respectively sections taken along the lines 3—3 and 4—4 in Figure 2 and illustrating the relation of the spindle, the latch bolt and the locking means employed.

Figure 5 illustrates a modified form of the invention wherein separate locking means for the latch bolt are provided at each end of the spindle.

Figure 6 is a section taken along the line 6—6 in Figure 5 and illustrating the spindle, latch bolt and lock in the latch bolt unlocked position.

Figure 7 is a view similar to Figure 6 but showing the same parts in locked position.

Figure 8 is a section taken along the line 8—8 of Figure 5 and illustrating the relation of the latch bolt, spindle and locking means in their respective unlocked position.

Figure 9 is a view similar to Figure 8 illustrating the spindle, latch bolt and locking means in their respective locked positions.

Figure 10 is a fragmentary view illustrating the construction of the spindle and the operating means provided for the latch bolt and taken along the line 10—10 in Figure 5.

Figure 11 is a section taken along the line

2

11—11 in Figure 5 and showing the parts in unlocked position while Figure 12 is a similar section but with the parts in locked position.

Figure 13 is a view generally similar to Figure 5 but wherein the latch bolt can be locked as well as the spindle.

Referring to the embodiment particularly shown in Figures 1-4, the structure includes a latch bolt generally indicated at 16 and which is adapted to be moved back and forth to release or to engage the usual keeper plate (not shown), this movement being accomplished by the spindle structure generally indicated at 17. The latch bolt is shown as mounted in a typical support as wooden door 18, the bolt being guided and restrained by a plate 19 secured by screws (not shown) in the door. The plate includes a circular extension 21 acting as a guide for the latch bolt.

The latch bolt 16 includes an end member 26 having a flat face 23 therein parallel to the axis of the latch bolt and an angular face 27 thereon, adapted to ride over a keeper plate provided in a door frame and lock against such a keeper plate in the usual manner. Flat face 23 rides against a flat side of the aperture in the keeper plate to position the bolt non-rotatably. Latch bolt 16 includes a latch plate generally indicated at 28 and having an H-shaped slot 29 formed therein to receive spring 31, the latter being positioned by legs 32 and 33 defining the H-shaped slot.

Mounted in a suitable aperture 41 in the door is a housing structure, generally indicated at 42 and having an opening 43 therein through which the latch bar 16 projects with spring 31 resting against the casing, so that any movement of the latch bar from that position in which it is shown in Figure 2 is resisted by compression of spring 31 between the casing and member 26.

Casing 42 includes a first dished member 44 generally cylindrical in outline and having a flat or base portion 45 provided thereon so that the member can be readily mounted in any circular aperture. Mounted upon the member 44 is a second dished member 46, this member being somewhat deeper than dished member 44 and having a flat or base portion 47 spaced from base portion 45 by the width of latch plate 28, as appears in Figure 2, to provide a slidably support therefor. The outer peripheral rim portions 48 and 49 are received within a rim portion 50 and a cover plate 51, the three being suitably secured together as by soldering, brazing or the like.

A tubular extension 53 is mounted upon the

second dished member 46, the two being secured together as by turning over a portion of plate 53, as indicated at 54, in suitable apertures in plate 47. A cover plate 56 is secured in position by screws 57, the latter engaging threaded holes 58 formed integrally in plate 45; the cover plate engages that side of the door opposite to the flanges 48 and 49 so that the casing 42 is securely held in position. A spring cover plate 59 is provided, the latter having a rim 60 fitting snugly over the peripheral edge of cover plate 56.

The extending ends 61 and 62 provided respectively upon cover plate 51 and tubular extension 53 are bent inwardly to provide bearing structures supporting a spindle structure generally indicated at 17 for sliding along its longitudinal axis.

The spindle structure includes a tubular member 71 having slots 68 on opposite sides thereof to pass slidably the latch bolt 28. This member can be formed of a flat plate from which one of the slots is cut, while the plate is flat; thereafter the plate is bent into cylindrical shape with the edges spaced apart to provide the other opposite slot. Mounted within and secured to the tubular member 71 is a tubular member 67, the latter being held in position by a pin 70 which extends through tubular member 69, the latter having slots corresponding to slots 68.

Mounted upon the pin 70 is a roller 72, the latter being engaged in a cam generally indicated at 73 and which is made in the form of a right angle triangle, generally an equilateral triangle in which one side 74 is parallel to the longitudinal axis of the latch bolt, one side 75 is transverse to the longitudinal axis while the base 76 is at an angle of about 45° to this axis. The normal position of the pin and roller in the cam is as appears in Figure 2 wherein the pin and roller are adjacent the rear of the bolt. In this position, the latch bolt can be moved rearwardly against the resistance provided by spring 31 without movement of the spindle. This type of motion is required, for example, to permit a door to swing into closed position without operating the lock. When the spindle is moved to the right in Figure 2 in the bearings provided by portions 61 and 62, pin 70 and roller 72 will move across the angular cam face 76 and will move the latch bolt rearwardly, thus serving to retract the latch bolt from engagement with a keeper plate and permit the door to open.

To provide a lock for the spindle, a sleeve 69 is rotatably mounted upon tubular member 67; this member likewise can be formed initially from a flat piece, the various cut-outs made, the piece then rolled into cylindrical form. Sleeve 69 includes a slot 82 at one end thereof in which an extension 83 is slidable, the extension being carried upon a tubular member 84 having a plurality of teeth 86 formed thereon. A spring 87 is positioned between door knob 88 and plate 89, provided in the tubular member 84 to bias the latter into engagement with cooperating and corresponding teeth 90 formed upon an end of the tubular member 67. The sleeve 69 and the tubular member 67 are locked in position by a tongue 91 in the sleeve 69 fitting into a slot 92 on the tubular member 67. The sleeve 69 includes an extension 96 thereon, having a slot 99 formed therein to receive and retain tongue 101 at the rear of the latch plate 28. Thus, to lock the spindle in the position shown in Figure 2, it is only necessary to rotate knob 88 approximately 45° and sufficiently to move teeth 86 and 90 relative to one another one tooth. Rotation in the op-

posite direction is effective to release the lock. The rear end of the latch plate 28 includes, in addition to tongue 101, a cam face 102 (Figures 2 and 3) which, when the spindle is locked, rides against a cooperating cam face 103 on extension 96. If the latch plate is moved rearwardly, the lock on the spindle is released, cam face 102 on the latch plate engaging cam face 103 on the extension 96 and rotating this to permit the latch plate to move past the extension and so releasing the spindle from engagement with extension 101; this can occur, for example, when, inadvertently, the spindle has been locked against sliding while the door is open and the door is then moved toward and into closed position.

Knob 88 is usually suitably fixedly secured to sleeve 69; in Figure 1, one or more ears 93 are bent into a cooperatively positioned notch in the shank of the knob.

At its opposite end, member 71 includes a plate 107 positioned therein and serving as a rest for a spring 108 which biases a ball 109 into engagement with an aperture 111 in a slidable plate 112, the latter including a tongue 113 movable through an aperture in member 71 and into engagement with a like aperture in the tubular extension 114 on the second knob 116. This permits the second knob 116 to be placed in position so that the lock can be readily assembled or disassembled.

In that modification shown in Figure 5, the slidable spindle can be locked selectively by either one of buttons 131 and 132 provided in the knobs 116 and 133. In this modification, knob 133 is mounted directly upon slidable spindle 137 and retains a rotatable button 131 in position in a recess 136 in slidable spindle 137. The button 131 carries a tubular extension 141 which is rotatable in a sleeve 142, the latter in turn being slidable in spindle 137 and having a tongue 143 fitting in a slot 140 in spindle 137. The end of sleeve 142 has a plurality of notches 144 therein engaging like notches 145 in sleeve 146. A blade 147 (Figures 5, 6 and 7) fits across the recessed ends of extension 141 and sleeve 146 and is notched to receive these; plate 45 carries a notch 148 therein to permit the blade 147 to pass to the left (Figure 5) in that position of the button shown in Figure 5. When the button is rotated and the blade 147 is moved out of registry with the notch 148 (Figure 7), then the spindle cannot be moved axially; plate 45 is provided with a recessed portion 149 to permit the blade to move out of registry and retain it against sliding. At the same time, tongue 151 on extension 141 is rotated into a position in which it rests against cam portion 152 on the end of the latch plate 28 so that, if the spindle is locked against sliding when the door is open, the latch plate can release the spindle and the door can be closed.

Button 132 in knob 116 can also be employed to lock the axially slidable spindle against sliding. In this instance, a sleeve 161 is rotatably mounted in the slidable spindle and includes a notch 162 therein. When the sleeve 161 is positioned as in Figures 5 and 11, the notches in spindle 137 and sleeve 161 are aligned and spindle 137 can slide axially. When sleeve 161 is rotated to take the notches out of alignment (Figure 12), the spindle cannot move axially because sleeve 161 abuts against the side of the latch plate 28. The sleeve 161 is latched in this position until released by turning a button 132 or the latch 28 is moved inwardly. Sleeve 161 and sleeve 146 are spaced apart by semi-cylindrical spacers 170

which are retained in place by pin 10. The button 132 has an extension 163 fitting slidably into cross piece 164 which is fitted into slots 165 in sleeve 161. The button 132 also carries a toothed extension 166 fitting cooperatively against toothed sleeve 167, the latter being pressed against extension 166 by spring 168 positioned between washer 169 and cross piece 171; toothed sleeve 167 is slidable in the spindle, tongue 172 thereon sliding in slot 173 in the spindle.

Knob 116 is removably mounted in the spindle by a disc member 176 having a tongue 177 fitting into an aperture in the knob shank. The disc is forced into the position in which it is shown in Figure 5 by cylinder 178, the latter having a conical end 179 fitting into a conical receptacle 181 in the disc 176. A spring 182 is positioned between the cross piece 164 and the conical end 179. When it is desired to remove the knob, tongue 177 is pressed inwardly to force the disc transversely and compress spring 182, whereupon the knob can be removed.

In that form of device shown in Figure 13, the sleeve 161 includes an extension 161A which, when the sleeve is rotated as by manipulation of button 132 into that position wherein the spindle cannot move axially, extension 161A is moved into position wherein it extends across the back of the latch plate; the latter is notched as at 104 for this purpose and one of spacers 170 is made shorter than the other to permit rotation of the extension 161A. Thus, the latch plate, as well as the spindle, can be locked against sliding.

From the foregoing I believe it will be apparent that I have provided a novel, rugged and simple form of lock which can be manufactured relatively inexpensively, utilizing sheet steel and brass and employing punch presses to form most of the parts.

I claim:

1. In a latch of the character described, a latch bolt slidably mounted in the latch and having a flat end thereon, a cam slot formed in said flat end, said slot being generally in the form of a triangle having its base extending substantially at 45° to the axis of the bolt and one side extending parallel to the axis of the bolt and the other side at 90° to said axis, a spindle slidably mounted in the latch and having a slot formed therein to receive said latch bolt flat end, a pin carried by the spindle and engaged with said cam slot to move the latch bolt axially upon axial sliding movement of the spindle, an extension on the end of said latch bolt flat end, and means rotatably supported on the spindle for engaging said extension to hold said spindle against sliding.

2. In a latch of the character described, a latch bolt slidably mounted in the latch and having a flat end thereon, a cam slot formed in said flat end, a spindle slidably mounted in the latch and having a slot formed therein to receive said latch bolt flat end, a pin carried by the spindle and engaged with said cam slot to move the latch bolt axially upon axial sliding movement of the spindle, an extension on the end of said latch bolt flat end, and means rotatably supported on the spindle for engaging said extension to hold said spindle against sliding.

3. In a latch of the character described, a latch bolt slidably mounted in the latch and having a flat end thereon, a cam slot formed in said flat end, said slot being generally in the form of a triangle having its base extending substantially at 45° to the axis of the bolt and one

side extending parallel to the axis of the bolt and the other side at 90° to said axis, a spindle slidably mounted in the latch, said spindle being tubular in section and having a continuous slot 5 along one side thereof to receive said latch bolt flat end, a pin carried by the spindle and engaged with said cam slot to move the latch bolt axially upon axial sliding movement of the spindle, an extension on the end of said latch bolt flat end, and means rotatably supported on the spindle for engaging said extension to hold said spindle against sliding.

4. In a latch of the character described, a latch bolt slidably mounted for movement back and forth along a first axis, a spindle slidably mounted for movement back and forth along a second axis at 90° to the first axis to move the latch bolt; a casing mounting the spindle and means for latching the spindle against sliding movement including a button having an extension thereon, a sleeve slidable in the spindle and supporting said extension for rotation, a blade extending transversely of the spindle and mounted on the extension for rotation between a spindle-sliding position wherein the blade is movable through an aperture in the casing and a spindle-locking position wherein the blade engages the casing.

5. In a latch of the character described, a latch bolt slidably mounted for movement back and forth along a first axis, a spindle slidably mounted for movement back and forth along a second axis at 90° to the first axis to move the latch bolt; and means for latching the spindle against sliding movement including a button mounted for rotation on the spindle and having a toothed extension thereon, a sleeve having a toothed end thereon engaged cooperatively with the toothed extension, a spring pressing said toothed end and toothed extension into engagement, a sleeve within said spindle and rotatable therewith, said sleeve having a notch adapted to fit over and pass the latch bolt.

6. In a latch of the character described, a latch bolt slidably mounted for movement back and forth along a first axis and having one end adapted to engage a keeper plate and its other end formed with a projecting tongue and with a cam; a spindle slidably mounted for movement back and forth along a second axis at 90° to the first axis to move the latch bolt; means for locking the spindle against sliding movement including a sleeve rotatably supported by the spindle and having a notch formed therein cooperatively adjacent said projecting tongue and a terminal face thereon cooperatively adjacent said cam, said sleeve being rotatable selectively between a position in which the spindle is free to slide and another position in which the notch in the sleeve is engaged with the tongue on the other end of the latch bolt to prevent the spindle from sliding axially and the terminal face is engaged with the cam for movement thereby.

7. In a latch of the character described, a latch bolt slidably mounted for movement back and forth along a first axis and having one end adapted to engage a keeper plate and its other end formed with a locking means, a spindle slidably mounted for movement back and forth along a second axis at 90° to the first axis to move the latch bolt; means for locking the spindle against sliding movement including a sleeve rotatably mounted within the spindle and rotatable selectively between one position in which the sleeve is engaged with the locking means on the other

end of the latch bolt to prevent the spindle from sliding axially and another position in which the spindle is free to slide; a cam on an end of the latch bolt, and a cooperating cam on said sleeve and engaged with the cam on the latch bolt when the sleeve is in latch bolt locking position, said cams being effective to rotate the sleeve upon sliding of the latch bolt.

8. In a latch of the character described, a latch bolt slidably mounted for movement back and forth along a first axis and having one end adapted to engage a keeper plate and its other end formed with an extension to provide a locking means; a spindle slidably mounted for movement back and forth along a second axis at 90° to the first axis to move the latch bolt; means for locking the spindle against sliding movement including a sleeve rotatably mounted on and surrounding a portion of the spindle and having an end thereon notched to engage an end of the latch bolt and rotatable selectively between one position in which the spindle is free to slide and a second position in which the notch in the sleeve is

5 engaged with the extension on the end of the latch bolt to prevent the spindle from sliding axially; and cam means provided on the end of the latch bolt and on the sleeve for rotating the sleeve

from the second position to the first position upon sliding of the latch bolt when the spindle is locked.
